YARN SPOOL FOR TUBE FRAMES.

Application filed September 4, 1926. Serial No. 133,593.

This invention relates to yarn spools adapted to be rotatably mounted in suitable bearings to deliver yarn for tuft weaving or other purposes, and it is intended to provide a journal construction that will permit interchange of spools used singly with those used as section or units of a multiple-section spool and will permit the endwise reversal of the spool, whether used singly or as a section of a series.

This improvement, while particularly intended to meet certain problems in tuft-yarn weaving, as exemplified in the manufacture of Axminster carpets and the like, is adapted to other purposes also in which multiple-section spools are used for the delivery of yarn or where interlocking spool sections are employed.

In the manufacture of Axminster rugs, whether of single width or of seamless multiple width, it is the practice to wind the different colored tuft yarn elements on the individual spools in a definite order to produce a predetermined pattern in the weaving. Such spools, identified by their individual pattern numbers, are stored for use when needed. This practice, however, requires the winding and the keeping in stock of a much larger number of spools and a larger supply of yarn than would be necessary if spools for single width tube frames could equally well be used as units or sections of the yarn-spool of a wide seamless loom tube-frame. Furthermore, it is often desired to reverse a particular pattern in a seamless rug so that the outside of the pattern will occupy interior portions of the rug or vice versa. Since the bearing apertures in the end brackets of a multiple spool-tube frame, as in those of a single spool tube frame, are necessarily small, while the bearings in the middle bearing stands or brackets are much larger, the pattern spools of a single tube-frame can not be mounted in the bearings of a multiple spool tube-frame. Neither can the spool sections of a wide tube-frame be reversed or interchanged with one another.

A further difficulty is due to the requirement that the spool sections be interlocked

with one another to insure equal rotation and equal delivery of yarn from the spool sections. All these difficulties will be readily understood by a consideration of prior art practice as illustrated, for example, in the U. S. patent, Hutchins, 1,067,656 and in other patents as well, from which it will appear that none of the three spool sections could be interchanged or reversed and none of them could be used in a single or narrow loom tube-frame.

The present improvement solves this problem by providing the ends of all yarn spools with two journals of different diameter adapted to fit respectively either the small bearing apertures of the end brackets of both wide and narrow loom tube-frames or the large bearings of the intermediate bearing brackets or stands of the wide loom tube-frames, the respective journal members being so related that either may function in its appropriate bearing without interference from the other. Moreover, provision is made for rotatably interlocking the spool sections together to cause uniform delivery of yarn from all sections simultaneously when the spools are used in wide loom tube-frames.

These and other features of the invention will be fully described in the following specification and will be defined in the claims annexed.

In the accompanying drawings we have illustrated specific embodiments of the principles of this invention, in which:

Figure 1 is a front elevation of a multiple spool tube-frame illustrating the mode of use of the improvement.

Figure 2 is a detail view showing one end construction of the spool in central longitudinal section.

Figure 3 is a detail end elevation of the end of the spool.

Figure 4 is an elevation on the plane 4-4 of Figure 2.

Figure 5 is a longitudinal central section through two adjacent interlocked spools showing the inter-engaging parts.

Figure 6 is a detail view of the yarn-clamp anchoring member.

Figure 7 is a detail longitudinal section of a modified construction of spool bearing support.

Figure 8 is an enlarged end view of the 5 projecting gudgeon shown in Figure 7.

Figure 9 is a detail view of the shiftable pindle and its support on the same scale as Figure 8.

Figure 10 is an end elevation showing the 10 assembled relationship of the gudgeon and shiftable pindle.

Figure 11 is a vertical section through adjacent spool ends showing both pins in central position.

15 We have herein shown the improvement applied specifically to a multiple spool tube-frame embracing a longitudinal carrier-bar 1, along one side of which is secured a row of tuft-tubes 2, and having, at 20 its ends, suspension brackets or ears comprising a chain-penetrating arm 3 and its associated spool-bearing member 4 with a movable hook latch 5, by which the tube-frame is engaged and disengaged from the 25 overhead carrier chains in the usual manner.

Beside the end spool brackets there are 30 also provided intermediate spool bearing brackets or stands 6, whose bearings 7 are of considerably larger interior diameter than the bearing recesses or holes formed in the end brackets.

Each spool comprises a barrel 8, which 35 may be solid as in Figure 2, or tubular as in Figure 7, and end heads 9 which are secured to the opposite ends of the barrel in any suitable manner, for example, by means of a sleeve 11 into which is inserted a counter-sunk central or hub portion 9^a of the disk 40 or head 9, to which it is fastened by soldering or otherwise. These heads usually have a peripheral flange 9^b for engagement with a brake. Secured to the spool structure are 45 cylindrical bearing gudgeons 10 which, in this case, are formed of hollow metallic cup-like members having inwardly projecting 50 prongs 10^a, adapted to pass through apertures in the hub 9^a of the spool head and to be clinched or bent down on the inner side thereof.

One feature of the present invention involves the use of a special construction for anchoring or attaching the yarn-gripping clamps one of which is attached to each 55 spoolful of yarn to keep the tuft elements properly separated for being threaded in to the tube frame. This clamp-attaching member comprises a centrally perforated disk 12, having peripheral projecting hooklike arms 12^a, arranged symmetrically around the axis 60 to be engaged by the end hooks or eyes of a contractile helical spring 14, which serves to secure the yarn-clamp 13 and hold it in place on the spool by reason of the pull exerted against the retaining hooks 12^a. As

shown, these hooks are turned inwardly and notched so that they hold the contractile spring under tension against allowing endwise movement or shifting of the yarn-spool. Should the yarn-spool be displaced endwise, 70 the engagement between the spring and its hook will not be released.

The gudgeon 10 is of a size to be journaled in the bearing 7 of the intermediate spool-bracket 6 but they are also provided with 75 centrally disposed bearing pintles 15 which are seated interiorly of the spool barrel and are normally thrust outward by a spring 16 thrusting against the inner end of the journal pin. It should be stated that the 80 locking prongs 10^a of the gudgeon pass through apertures in the disk 12, as well as those in the hub 9^a.

As will be understood, when two spool ends are brought together the central pintles 85 15 thrust against each other and serve to push each other inwardly until their outer ends are almost flush with the end faces of the gudgeons 10. As it is often desired, however, to interlock the two adjacent spools 90 in a tube-frame together so as to insure equal delivery of the yarn from both, we have made provision for effecting such interlocking engagement by shifting one of the 95 pintles from concentric to eccentric position.

With this object in view the end of the hollow gudgeon 10 is provided with an annularly arranged series of apertures any one of 100 which is adapted to receive the projecting end of the co-acting pindle when the pindle is shifted to eccentric position. To permit 105 this shifting movement the hub 9^a is slotted, as shown at 9^c, to permit this swinging or lateral movement of the pindle, the slot being narrow enough, however, to form an abutment for the shoulder 15^a formed by reducing the outer portion of the pindle to smaller 110 diameter than the inner portion so as to limit the outward thrust of the spring 16. A guide washer 15^b is applied to the inner 115 end of the pindle to guide the inner end and to receive the thrust of the spring 16. The tip end 15^e of the pindle is also preferably reduced somewhat in diameter to make it 120 smaller than the portion passing through the 125 gudgeon.

In addition to the apertures 10^b formed in the outer end of the gudgeon 10, there is a 130 sort of keyhole slot or hour-glass slot 10^c, formed by joining a centrally disposed aperture with one of the surrounding interlocking apertures as shown at 10^e. The narrow part of this slot will not permit the intermediate portion of the pindle 15 to swing from concentric to eccentric position, but in 135 order to do this the pindle must be pushed in until its relatively narrow tip lies in position to pass through said communicating slot and in that position the pindle may be adjusted to either eccentric or concentric position. In 140

this eccentric position it will be located properly to penetrate any one of the holes 10^b of the opposing gudgeon of the adjacent spool with which it is brought into register.

From the foregoing it will be seen that identically the same spool may be used either in a single spool tube-frame for narrow looms, in which the spool brackets are like the end brackets shown in Figure 1, or it 10 may be used in either the end position or an intermediate position of a multiple spool tube-frame because it has the large gudgeons adapted to fit the intermediate stands or 15 brackets of a multiple spool tube-frame and also has the small pintles adapted to fit the small bearing apertures in the end spool brackets and these are so arranged that neither interferes with the other or prevents the other from functioning properly. 20 For the same reason any spools of the multiple series can be reversed end to end.

In Figures 7 to 10 is illustrated a modified construction intended for the same purpose. In this case the hollow gudgeon 20, of very 25 similar construction to that previously described, is secured to the hub 9^a of the head 9 of the spool barrel. In the outer end of the hollow gudgeon 20 is bored, at a proper distance off the center, a large circular aperture 20^b, said aperture being further cut away beyond the center of the gudgeon and also toward its periphery to form two approximately semi-circular recesses 20^c, communicating directly with the main aperture at 20^b. The interior aperture 20^c is drawn on an arc concentric with the center of the gudgeon and the outer aperture 20^b is drawn on a similar circle or radius. Inside of the gudgeon is mounted, 30 eccentrically thereof, a disk 23 having a centrally disposed inwardly projecting guide-pin 24. This disk also carries an outwardly 35 projecting pintle 21 at its extreme edge portion which is transversely notched at 21^a for a purpose to be described. Diametrically 40 opposite to the location of the pintle 21, the disk is formed with an approximately semi-circular recess which, in conjunction with the exterior recess 20^c of the gudgeon 20, 45 forms a circular aperture for the reception of the pintle of an adjacent spool placed in end to end relation to a similar spool. A 50 helical spring 25 acts to normally thrust the disk 23 outwardly against the inside end 55 face of the gudgeon 20. The disk is enough 60 larger than the opening 20^b so that its edge portion bears against the inner face and allows the disk to be rotated, carrying the 65 pintle 21 with it from a position that is central to the gudgeon to a position 180 degrees therefrom, that is, eccentric to the gudgeon.

Normally the outer side of the pin 21 seats itself in either recess 20^c, according to 65 its position of adjustment. To permit the

disk to be rotated or adjusted from one position to the other a notch is cut through its outside at a short distance from the outside face of the disk 23, so that normally the uncut portion of the pin interlocks with 70 either recess 20^c to prevent accidental displacement while, by pressing the disk and pintle inwardly against the spring tension, notch 21^a in the pin is brought into alignment with the bounding edge of the orifice 20^b, and in this position the disk may be 75 rotated to engage the pin with the opposite notch or recess 20^c. It will, therefore, be seen that the pintle 21 and the recess 23^a in the disk 23 are shiftable to occupy either 80 the concentric position or the eccentric position, according to the use to which the pintle is put, whether to serve as a central bearing member or as an eccentric spool-interlocking member. 85

In some cases it is preferred not to make use of any interlock between the spools, hence to meet such a situation the pins of two adjacent spools may be left in the central position, each abutting directly against 90 the other so that both are retracted to a position in which their tip ends are practically flush with the transverse or end wall of the spool. In such position, however, there is a possibility that one of them might shift 95 sidewise to eccentric or interlocking position. Therefore when it is desired to provide for such a condition, the end or transverse wall of the gudgeon may be inset or countersunk inward from the outer edge of the gudgeon, 100 as shown in Figure 11. In this case the gudgeon has its transverse wall, of the same construction as before, inset a distance from the outer end a little greater than the length 105 of the reduced tip 15^c so that when the end 110 of the tip is substantially flush with or even slightly inside the outer end of the gudgeon 10, the shoulder projects slightly beyond or outside of the transverse pin-retaining wall. 115

It will, therefore, be seen that the principle of construction allows complete adaptation to every desired condition of use, for it will be obvious upon an inspection of Figure 11, that whether the transverse or pin-locating wall be located at the extreme end 120 of the gudgeon or inset therefrom the pin may still be adjusted to interlocking position by further depressing it inward to bring the reduced tip into the narrow passage connecting the central hole with one of the eccentric holes so that the insetting of this member does not interfere with its function of locating the pin for interlocking adjustment as well as for non-interlocking 125 adjustment.

What we claim is:

1. A yarn spool for delivering yarn embracing spool sections adapted to be rotatably supported end to end, journal gudgeons 130 secured to the ends of the spool sections for

- rotatably supporting the spool sections in intermediate bearings, and adjustable pintles mounted in said gudgeons to serve according to their adjustment either as a supporting journal for the spool section or as a means for rotatively interlocking adjacent spool sections together to cause equal rotation of adjacent spool sections thus interlocked.
10. A yarn spool adapted to be rotatively mounted in bearings for the delivery of yarn, comprising a barrel, and gudgeons adapted to form supporting journals fitting the bearings of the intermediate stands of a tube frame, and pintles arranged to project centrally of said gudgeons to fit bearings in the tube frame end brackets, said pintles being displaceable from their normal spool-supporting positions to permit the gudgeons of two adjacent spools to be brought together.
15. A yarn spool adapted to be rotatably mounted in bearings for the delivery of yarn, comprising a barrel, journal gudgeons secured to the ends of the barrel and journal pintles adjustably mounted in the gudgeons and shiftable from co-axial spool-supporting position in said gudgeon to eccentric position for interlockingly engaging the gudgeon of an adjacent spool.
20. A journal for a yarn spool embracing a hollow cylindrical gudgeon adapted to be secured to the end of a yarn spool, a pintle coaxially mounted in said gudgeon to project centrally therefrom and shiftable to eccentric position relative to said gudgeon to form interlocking engagement with the gudgeon of an adjacent spool to cause both spools to rotate equally for the delivery of yarn.
25. A yarn spool embracing a barrel and cylindrical end gudgeons adapted to form journals for rotatably supporting the spool in appropriate bearings, said gudgeons being provided with apertures in their end faces, equally distant from the spool axis, adapted to receive a pintle projecting from the gudgeon of an adjacent spool, and having also a projecting pintle that is adjustable from central position where it serves as a bearing journal, to eccentric position to penetrate off centre apertures of a similar gudgeon to interlock two adjacent gudgeons together for equal rotation.
30. A yarn spool embracing in its construction a barrel, hollow end gudgeons secured to said barrel and projecting axially outward therefrom to form spool-supporting journals, said gudgeons being provided with a pintle-receiving aperture in their ends one of which is centrally located, and a pintle arranged to project from the central aperture and shiftable therefrom to project through another aperture located eccentrically of the gudgeon.
7. A yarn spool embracing a barrel, hollow gudgeons secured to the barrel to form end journals to rotatably support the spool in appropriate bearings, each gudgeon having a central aperture and also a concentrically disposed series of apertures adapted to receive a projecting pintle of an adjacent spool, the central apertures having communication with one of the other apertures by means of a slot, and a spring-pressed pintle arranged to project outwardly from said gudgeon through the central apertures or through the outer aperture connected therewith according to its position of adjustment.
8. A yarn spool embracing in its construction a barrel, sheet metal ends secured thereto by means of a countersunk hub portion, hollow gudgeons secured in said hubs to project axially therefrom and form spool-supporting journals, journal pintles carried by said gudgeons and adapted to project endwise therefrom either centrally thereof or in off centre relation to the gudgeon in order to serve either as a spool-supporting journal or an interlocking connection with a similar gudgeon.
9. A yarn spool embracing a barrel, end gudgeons secured thereto for rotatably supporting the spool in bearings of corresponding dimensions, movable journal pins mounted interiorly of the gudgeons to rotatably support the spool in bearings corresponding to their dimensions and to form, when desired, interlocking connection between two end spools to insure equal rotation of both spools.
10. In a tube frame the combination with a carrier having spool-supporting brackets at its opposite ends and one or more intermediate spool-supporting brackets arranged to support a plurality of spools end to end, and a series of spools rotatably mounted in said bearings, each spool having at each end inner and outer concentric bearing elements dimensioned respectively to coact with corresponding bearing elements in the end brackets and in intermediate brackets whereby either end of each spool may be rotatably mounted in either end bracket or in any intermediate bracket.
11. A yarn spool for tube frames embracing in its construction a barrel, spool-supporting gudgeons secured at each end thereof to rotatably support the spool, a transverse pintle-locating wall secured inside said gudgeon at a distance from the outer end edge of the gudgeon, said wall being perforated and slotted, and a longitudinal pintle adjustable at will from central position to eccentric position in said wall to engage a corresponding pintle or its containing gudgeon when two spools are placed end to end in a tube frame.
12. A yarn spool for tube frames embracing a barrel, bearing gudgeons projecting

from the ends thereof, each gudgeon being provided with a radially slotted and eccentrically perforated transverse pintle-locating member, a pintle located inside said journal 5 to project through said slot beyond the outer end of the gudgeon and adjustable in said slot to either central position or to eccentric position, the slot being narrowed intermediate of its central and outer portion to 10 retain the pintle in either position of adjustment.

13. A yarn spool for a tube frame or the

like embracing a barrel, end journals for rotatably supporting the spool in bearings and a clamp-anchoring device embracing a body 15 portion, and projecting prongs arranged around and in proximity to said journals in position to releasably retain clamp-attaching members.

In witness whereof, we have subscribed 20 to the above specification.

EDGAR F. HATHAWAY.
WALTER BIXBY.
